UNITED STATES PATENT OFFICE.

EDWARD F. KAPUS, OF ST. JOSEPH, MISSOURI.

COMBINED SASH LOCK AND FASTENER.

No. 913,730.

Specification of Letters Patent.

Patented March 2, 1909.

Application filed October 28, 1908. Serial No. 459,910.

To all whom it may concern:

Be it known that I, EDWARD F. KAPUS, a citizen of the United States, residing at St. Joseph, in the county of Buchanan and State of Missouri, have invented certain new and useful Improvements in Combined Sash Locks and Fasteners, of which the following is a specification, reference being had therein to the accompanying drawing.

- 10 My invention relates to improvements in combined sash locks and fasteners, in which the objects are to provide a neat and substantial mechanism, which will automatically draw together and lock the two sashes 15 of a window, be positive and reliable in its automatically operated movements, and which, to automatically lock, shall be started by but one quickly and easily accomplished movement.
- 20 A further object is to combine the parts of a window lock with other parts, in such manner, that a window fastener is formed of said combined parts, whereby said two sashes are automatically fastened and drawn together, in such manner as to allow of the 25 upward and downward movement together, of the thus fastened sashes, and thereby permit ventilation, either below, above, or both below and above said fastened sashes. Also, 30 to so construct and arrange the parts, that they will automatically close the crevice, ordinarily found between the parting rails of said sashes, when either used as lock, or as a fastener, thereby preventing admission 35 of air and dust, and also preventing said sashes from rattling, and to so situate and combine the parts, that they shall, in an ordinary sense, be inaccessible and inoperable from the outside of said sashes, thus 40 providing what is ordinarily termed a burglar proof lock and fastener.

I attain these objects by the mechanism illustrated in the accompanying drawing, in which:—

- 45 Figure 1 is a vertical section, cut on the line X' X', seen in Fig. 4, showing the parts in locked position. Fig. 2 is a view from the outside, showing the parts in fastened position. Fig. 3 is a top plan, showing the 50 parts in both unlocked and unfastened position. Fig. 4 is a bottom plan of the parts in locked position, the parting rails of the sash being omitted, to avoid obscurity. Fig. 5 is a bottom plan of the parts in set position, the parting rails and the lower portion 55 of the catch-bar being omitted, to avoid
- obscurity. Fig. 6 is the same as Fig. 5, except that the parts are shown in fastened position. Figs. 7, 8 and 9, illustrate one of the various forms of catch-bars, that may be 60 made.
- My invention in its preferred form, comprises a case 1, provided with a slot 1', formed in the top thereof; a latch lever 2, slidably and pivotally mounted on said case; 65 a pivot stud 3, preferably formed integrally with said lever, projects downward therefrom, through said slot; a semi-annular cam 4, rigidly secured on the lower end of said stud; a crank-pin 5, projecting from the 70 lower surface of said cam, and preferably formed therewith; a spiral spring 6, having one of its ends pivotally secured on said crank-pin and its other end pivotally secured to the front portion of said case. 75 Latch lever 2 is provided with an upwardly projecting, semi-annular locking flange 7, formed integral therewith, and having an inclined upper surface 9, said flange and its inclined surface being arranged eccentric 80 to stud 3. Said latch lever is also provided with a hook 8, on one end thereof, and a thumb piece 2', on the opposite end of said lever. Hook 8 is provided with a sloped surface 9', for deflecting said hook, as hereinafter described. A catch-bar 10 is provided, having notches 11, formed in one edge thereof, and a projection or shoulder 12, formed longitudinally on its outer side. The lower portion of said catch-bar is suitably curved to pass downward outside of bearing piece 13, and is provided with an inwardly projecting sleeve 14, formed integral with the lower portion of said catch-bar, and rotatably secured in aperture 14' in 85 said bearing piece, by rivet 15, which passes through the inwardly projecting flange 16, formed on the inner end of said sleeve, and through spring washer 17, and is headed on both of its ends. Said spring washer rests 90 against the inner surface of bearing piece 13, and elastically draws the lower portion of catch-bar 10 against the outer surface of said bearing piece, thereby providing an inexpensive, substantial and well alined pivotal 95 securing means for securing said catch-bar to said bearing piece, and frictional holding means, for movably holding said catch-bar at any desired angle to said bearing piece, when it is desired to rotate said catch-bar, 105 to thereby remove the same from such positions as will obstruct the ordinary operation 110

of cleaning glass 23. Said catch-bar is stopped at erect position by contact of its foot 18, on stop flange 26, formed with bearing-piece 13. Bearing piece 13 is extended 5 inward at its upper end, to form bracket 27, on the end of which is formed the downwardly projecting locking flange 13', adapted to be engaged by the locking flange 7, for locking parting rails 19 and 21 together. 10 Said rails form a part of the respective sashes 19' and 21'.

In the installation and operation of my invention, bearing piece 13 is secured by screws 20, at or near the center, on the upper 15 surface of the lower or parting rail 19, of the upper sash 19' of any ordinary window, and case 1 is secured in register with said bearing piece, on the upper or parting rail 21 of the lower sash 21' of said window, by 20 screws 22. In practice, the operator, in locking said sashes, by thumb-piece 2' rotates lever 2 from stop stud 1'', (seen in Fig. 3,) until crank-pin 5 has thereby been carried to the point, indicated by dotted lines 5', in 25 Fig. 4; after which spring 6 draws said crank-pin to the position seen at 5, thereby rotating lever 2, carrying flange 7 into engagement with flange 13', in the position seen in Figs. 1 and 4, which locks rails 19 and 21 together. It will be seen and understood, that the inclined upper surface 9, of flange 7, is carried under, and presses upward against the bracket 27, thereby forcing rail 19 and its sash 19', upward.

35 While the described rotation of lever 2 is taking place, the semi-annual periphery of cam 4 is thereby rotated from the position indicated in Fig. 3, to the position shown in Fig. 4, in which position said cam has its 40 longitudinal movement stopped by the outer wall of case 1, thus forming a rotatable abutment for stud 3 and preventing outward movement of flange 7, which, (due to its 45 position, eccentric to stud 3,) draws flange 13', inward, and thereby draws rail 19 from the position seen in Fig. 3, to the position seen in Fig. 1, thus closing crevice 28, seen open, in Fig. 3, thus tightly and substantially locking the described sashes. If the 50 operator so desires, he may assist spring 6 in its automatic operation, by applying pressure to thumb-piece 2'.

To unlock the locking parts, the operator 55 draws thumb-piece 2' overcoming spring 6, until said spring has passed the center of stud 3, after which spring 6 automatically draws the parts to the position seen in Fig. 3, with lever 2 stopped against stop stud 1''. To fasten and draw said sashes together, in 60 proper position for ventilation, as seen in Fig. 2, thumb-piece 2' is pushed toward catch-bar 10, and rotated until the sloped surface 9', of hook 8, has deflected said hook and has passed said catch-bar, after which, 65 spring 6 draws said hook into engagement

with the catch-bar 10, in set position, seen in Fig. 5. When parts are in set position, the raising or lowering of either one of said sashes, brings one of notches 11 in register with hook 8, which is then automatically 70 drawn into engagement therewith, by spring 6, in fastened position, seen in Fig. 6. Spring 6 continues to pull said catch-bar, after being thus fastened, and thereby draws rails 19 and 21 toward each other, and thus 75 prevents their sashes 19' and 21', from rattling.

While I have shown and described my invention in the foregoing manner, it is evident shoulder 12, on catch-bar 10, could be 80 supplemented or augmented in various ways, by the forming of recesses in said catch-bar, without departing from the spirit of my invention, one of such recessed catch-bars being shown at 10^b, in Figs. 7, 8 and 9, in 85 which hook 8^a is adapted to pass into engagement with shoulder 12^a, in set position, seen in Fig. 7 and to enter recesses 12^b, and be thereby secured in place when said hook is in notches 11^a, in fastened position, seen 90 in Fig. 8. In this latter position, said hook rests in recess 10^a, formed in the outer side of said catch-bar, for so inaccessibly placing the inner edge of said hook, in said catch-bar, that an unfastening instrument, (not 95 shown,) forced upward through crevice 28, could not be inserted between said hook and catch-bar.

Having fully described my invention, what I claim as new, and desire to secure by Letters Patent, is:—

1. In a combined sash lock and fastener, a case having a slot in the top thereof, and a stop stud secured thereon, and securing means, for securing said case to the upper rail of the lower sash of a window, in combination with a lever, mounted on said case, and provided with a thumb-piece, an upwardly projecting locking flange and a fastening hook, formed therewith, as specified; a pivot stud, for said lever, extending downward therefrom, through the slot of said case; movable abutting means, on the lower end of said stud; spring actuating means; in said case, for actuating said abutting means and lever; a bearing piece, provided with securing means, whereby said bearing piece is secured to the lower rail of the upper sash of a window; said bearing piece being provided with a bracket, extending inward therefrom, and a downwardly projecting flange formed with said bracket, adapted to be engaged by said locking flange; a catch-bar, having notches formed therein and a shoulder formed thereon 125 adapted to be engaged by said hook, as specified, and pivotal securing means, whereby said catch-bar is pivotally secured to said bearing piece.

2. In a mechanism of the character de- 130

- scribed; a case, having a slot, formed in the top thereof, and provided with a stop stud, secured thereon, and securing means whereby said case is secured on the upper rail of the lower sash of a window; a lever, provided with a thumb-piece on one end thereof, and a hook, on the other end, adapted to be moved into engagement with the notches of a notched catch-bar; a pivot stud, extending downward from said lever, and through said slot; a semi-annular cam, secured on the lower end of said stud, and adapted to form a movable abutment for said stud; a crank-pin, on said cam; a spring in said case, having one of its ends pivotally secured to said crank-pin and its other end pivotally secured to the front portion of said case.
3. In a mechanism of the character described, the combination with a catch-bar, having notches formed in one of its edges and provided with a shoulder, formed longitudinally thereon; of a spring actuated hook, movably secured on the upper rail of the lower sash of a window, and adapted to be moved by said spring, into said notches and in engagement with said shoulder, for securely holding said hook in said notches, and pivotal securing means, whereby said catch-bar is pivotally secured to the lower rail of the upper sash of a window.
4. In a mechanism of the character described, in combination, a bearing piece, having an aperture therethrough, and provided with securing means for securing said bearing piece on the lower rail of the upper sash of a window; a suitably notched catch-bar, provided with a shoulder, formed longitudinally thereon, and an inwardly projecting sleeve formed with the lower portion thereof; adapted to be inserted in said aperture in said bearing piece, said sleeve being provided with an inwardly projecting flange formed on its inner end; a spring washer, secured on said flange; and a rivet passing through said flange and washer, for securing said flange and washer together, after said parts are placed as shown, the whole arranged to form frictional and pivotal securing means, for pivotally securing and movably holding the lower portion of said catch-bar to said bearing piece.
5. In a mechanism of the character described, a catch-bar, having notches and recesses formed therein and a shoulder, formed longitudinally thereon, and securing means for securing said catch-bar to the lower rail of the upper sash of a window; said catch-bar being adapted to be engaged by a spring actuated hook, adapted to be moved by said spring, against said catch-bar and in engagement with said shoulder, for securely holding said hook in set position, as specified; said recesses being adapted to be engaged by said hook, for securely holding said hook, in said notches, when in fastened position, and adapted to provide inaccessible emplacement for said hook, when in said fastened position.

In testimony whereof I affix my signature in the presence of two witnesses.

EDWARD F. KAPUS.
